(No Model.)

B. J. H. DE VRY,

DEVICE FOR SIMULTANEOUSLY MOVING DOUBLE DOORS.

No. 503,361.

Patented Aug. 15, 1893.

UNITED STATES PATENT OFFICE.

BERNHARD J. H. DE VRY, OF CHICAGO, ILLINOIS.

DEVICE FOR SIMULTANEOUSLY MOVING DOUBLE DOORS.

SPECIFICATION forming part of Letters Patent No. 503,361, dated August 15, 1893.

Application filed March 20, 1893. Serial No. 466,822. (No model.)

To all whom it may concern:

Be it known that I, BERNHARD J. H. DE VRY, a subject of the Emperor of Germany, residing at Chicago, in the county of Cook and State of Illinois, have invented a new and useful Improvement in Devices for Simultaneously Moving Double Doors, of which the following is a specification.

My invention relates to an improvement in the class of folding doors in which each set of doors comprises two relatively sliding members co-operating to close the door-way when brought together and adapted to be separated, by sliding them apart, to open the door-way; and it relates, particularly, to connecting means provided on such doors, whereby movement of either member, in opening or closing it, is transmitted to the other, simultaneously to open or close it.

My object is materially to simplify the construction and improve the operation of the connecting-means referred to, and particularly the means for the purpose shown and described in Letters Patent of the United States No. 376,946, dated January 24, 1888, with relation to which, especially, I desire to avoid the use of rack-bars and sprocket-wheels, which are found, in practice, to be undesirable by reason of their great weight, and expense and the excessive friction they produce.

In the accompanying drawings, Figure 1 represents an elevation of the upper portion of a pair of sliding doors with my improved device attached; and Fig. 2 is a section taken at the line 2 on Fig. 1 and viewed in the direction of the arrow.

A and A' denote two sliding doors suspended, respectively, on carrier-bars B and B' by the hangers r, the bars resting on shafts q of wheels C which ride upon the rails p. Above the respective doors A and A', are journaled, in the overhead casing, the pulleys D and D', each of which is provided with two parallel peripheral grooves; and a crossed cable D² connects the two pulleys at corresponding grooves therein.

E is a cable or wire fastened at one end to the upper end of the door A at o, passed thence over a suitable stationary guide, as the pin n, near the rear end of the carrier-bar

B, and under and about the pulley D in the other groove from that containing the cable D²; and from the pulley D the cable E is passed over a stationary guide, as the pin n', near the forward end of the carrier-bar, to, and fastened at its opposite end at, o', on the upper end of the door. The points o and o', at which the ends of the cable E are fastened are preferably eyes having threaded stems to screw into the upper end of the door A, whereby any slack in the cable may be taken up by turning the eyes to drive their screw-stems the farther into the wood; and it is preferred, but not necessary, that the cable E be crossed, as shown, between the points o and o'.

E' is a cable or wire for the door A', arranged in all respects like the cable E for the door A. That is to say, it has one end fastened to the upper end of the door at o²; is passed thence over a suitable stationary guide, as the pin n² near the rear end of the carrier-bar B', and about the pulley D' in the other groove from that containing the cable D²; and from the pulley D' the cable E' is passed over a stationary guide, as the pin n³ near the forward end of the said carrier-bar, to, and fastened at its opposite end at, o³ on the upper end of the door. The parts o² and o³ may be counterparts of the parts o and o'.

From the foregoing description of the mechanism the operation will be understood to be as follows: As illustrated the doors A and A' are shown to be open or partly open. Obviously, if either door is pulled to, the strain on the respective end of the cable E or E' will revolve the adjacent pulley D or D' in one direction, whereby, through the medium of the cross-belt D², the other pulley will be revolved in the opposite direction and cause the other door to be simultaneously pulled to; and if either door be pushed back, obviously, the connections will cause the other door to be simultaneously opened.

What I claim as new, and desire to secure by Letters Patent, is—

1. In a device for simultaneously moving double sliding doors, the combination with the doors of the double-grooved pulleys D and D' having the crossed-belt connection D², the carrier-bars B and B' by which the doors are hung on the track p, and cables E and E',

passed respectively about the said pulleys and overguides and fastened at their ends to the respective doors, substantially as and for the purpose set forth.

5. 2. In a device for simultaneously moving double sliding doors, the combination with the doors A and A' of screw-eyes in the upper ends of the doors, hanger-bars B and B' on rollers and by which the doors are hung on the track p , double-grooved pulleys D and D' above the doors and connected by a crossed belt D², a cable E fastened at its opposite

ends to the screw-eyes on the door A and passing over guides n and n' about the pulley D, and a cable E' fastened at its opposite ends to the screw-eyes on the door A' and passing over guides n² and n³ about the pulley D', the whole being constructed and arranged to operate substantially as and for the purpose set forth.

BERNHARD J. H. DE VRY.

In presence of—
M. J. FROST,
W. N. WILLIAMS.
